UNITED STATES PATENT OFFICE.

LEE S. CHADWICK, OF SHAKER HEIGHTS VILLAGE, OHIO, ASSIGNOR TO PERFECTION STOVE COMPANY, OF CLEVELAND, OHIO, A CORPORATION OF OHIO.

SHEET-METAL CONSTRUCTION.

Application filed January 27, 1922. Serial No. 532,228.

To all whom it may concern:

Be it known that I, LEE S. CHADWICK, a citizen of the United States, residing at Shaker Heights Village, in the county of 5 Cuyahoga and State of Ohio, have invented a certain new and useful Improvement in Sheet-Metal Constructions, of which the following is a full, clear, and exact description, reference being had to the accompanying 10 drawings.

This invention relates to sheet metal fabrication and more particularly to an improved construction that is especially suitable for use in sheet metal stoves and like structures.

15 The objects of the invention are to provide a sheet metal construction for stoves and the like which is strong and durable and, as to the joints, is rigid; which expedites and cheapens manufacture; which greatly facilitates assembly and disassembly, the latter, as for the purpose of shipment and storage; which is of such nature as to insure accuracy in the fitting together of the parts; and which is very simple in structural details enabling those unskilled in the art to readily 20 assemble it.

These objects, and others hereinafter appearing, are obtained in the construction illustrated in the drawings accompanying and 25 forming a part hereof and wherein Fig. 1 is a partial front elevation of a sheet metal stove structure embodying my invention; Fig. 2 is a detail of the corner construction on a scale somewhat enlarged over that of 30 Fig. 1; Fig. 3 is a plan view of the corner construction with the corner of the top broken away to show the parts therebelow in elevation; Figs. 4 and 5 are sections on the respective lines 4—4 and 5—5 of Fig. 2; 35 and Fig. 6 shows in perspective several of the parts of the structure in separated condition yet suggesting their relation in the structure.

The particular structure wherein I have 40 shown my improvements incorporated is that of a sheet metal stove of the class in which liquid fuel burners are employed, the same comprising, generally, a top, a sub-structure whereon the top is supported, and 45 legs which sustain the sub-structure at a suitable elevation. The top is designated 1, an end panel is indicated at 2, one of the legs is shown at 3, the base whereon the burners (not shown) are supported is design-

nated 4, and a drip pan is indicated at 5. 55 All of these parts are of sheet metal and the top has a depending peripheral flange 6, while the front edge portion of the end panel 2 is turned inwardly at right angles to the plane of its body portion to provide a flange 60 7. It is to be understood that the two ends of the stove are identical, and a back wall 8 extends from one end panel to the other and from the top 1 to the base 4.

Within each of the top corners of the 65 structure there is a bracket 10, shown in perspective in Fig. 6, and the same comprises three parts each of which is disposed at right angles to the other two, and they consist of a 70 triangular part 11 that is arranged for engagement with the under surface of the top 1, and parts 12 and 13 which overlie the adjacent portion of the end panel 2 and the upper end of its flange 7, respectively. The 75 brackets 10 are interchangeable among the four top corners of the structure, and when used in the rear corners the parts 12 and 13 engage the end panels 2 and the back wall 8. The parts 12 and 13 are secured to the 80 elements which they overhang by rivets, or the like, 15, and also by having lugs 16 at their lower ends engaged through slots 17 in said elements and to the rear of which they are turned downwardly, as clearly 85 shown in Fig. 4. By this means, the brackets are securely attached to the aforesaid elements and effectually maintain them in right angular relation to each other, or whatever angle there might be between the parts 12 and 13, assuming that in certain constructions it might be desirable to have said elements disposed at other than right angles 90 toward each other. Attention is called to the fact that throughout the region of the corner the end panel 2, and the part disposed at right angles thereto, which is the angle 7 in the present illustration, are cut 95 away downwardly from their upper ends to a depth equal to or slightly greater than the thickness of the part 11 of the corner bracket, so that when the bracket is attached to said elements its upper surface will be in the plane of the major portion of the upper edge of the end panel. The panel is flanged 100 inwardly throughout such major portion, as indicated at 20, and the back panel is likewise flanged inwardly, as shown at 21 in Fig. 2, so that a satisfactory bearing surface is 105

provided for the top 1 along each end and along the back.

Triangular gussets 25 afford a support for the front portion of the top wall inwardly 5 some distance from the ends. These gussets are shown as of sheet metal, and extending rearwardly from the top and side edges of the triangular front portion of each gusset are flanges 26 and 27, respectively, while 10 stability is imparted to the gusset by a flange 28 that is turned inwardly along the inclined edge of the front portion, such quality being further enhanced by the bead 29 which is formed in said triangular portion 15 adjacent and parallel to said inclined edge.

Tongues 30, strengthened by beads 31, are struck from the parts 12 and 13 of each corner bracket 10, and these tongues project outwardly and then downwardly from 20 said parts and are spaced from the outer surfaces thereof a distance substantially equal to the aggregate thickness of the metal whereof the gusset 25 and leg 3 are 25 formed.

Each leg 3 consists of an angle member, the flanges whereof are gradually reduced in width from the base 4 to the lower end 30 of the leg, the leg flaring outwardly somewhat toward its lower end, as shown in Fig. 1.

In assembling the parts, the gusset 25 at each end of the structure is engaged about the front flanged edge of the corresponding 35 end panel 2 in the manner illustrated in Fig. 6 and it is slid upwardly until the inner end of its flange 26 engages the underneath surface of the triangular part 11 of the bracket 10, the free end of the flange 26 yielding downwardly somewhat so that the outer end portion of the flange is in substantially the plane of the upper surface of the part 11 and in similar relation to the flange 20 of the end panel 2. When raised 45 to such an elevation, the upper edge of the flange 27, and the portion of the triangular face of the gusset adjacent thereto are beneath the tongues 30 of the bracket. The leg 3 is then slid up beneath the tongues 30 and brought into firm engagement with their outwardly extending portions, at which 50 time apertures in the flanges of the leg register with holes in the base 4 and end panel 2 so that bolts 35, or the like, may be engaged therethrough to firmly bind the parts together. This insures the leg from 55 becoming disengaged from the tongues of the corner bracket. The lower portions of the four legs of the structure are tied together through the drip pan 5 to which they 60 are attached by bolts 36, or the like. The top 1 rests upon the flanges 20 and 21 of the end panels 2 and back wall 8, respectively, while the flanges 26 of the gussets 25 engage 65 the under surface of the top, as indicated in Fig. 2. Bolts 37, or their equivalents, are passed through holes in the top and through registering holes 38 in the triangular parts 11 of the brackets 10 to bind the top to the under structure, while bolts 39, or their equivalents, are engaged through the holes 40 of the flanges 26 and through registering holes in the top.

From the foregoing disclosure it will be seen that my invention provides a simple, inexpensive and comparatively rigid construction for sheet metal structures, and my improvements insure accuracy in the fitting of the parts together, and greatly facilitates assembly and disassembly.

In this latter connection it may be well to point out the fundamental purpose of the lugs 16 which extend from the lower ends of the parts 12 and 13 of the corner brackets and are engaged through slots 17 in the elements which said parts overlie. By such a construction, blunt ends are avoided against which the gussets 25 and the upper ends of the legs 3 might abut when inserting them upwardly into the sockets provided by the tongues 30, which, it will be observed, are concealed by the depending flange of the stove top.

Having thus described my invention, what I claim is:

1. In a construction of the character set forth, the combination of three walls disposed at a given angle one to the others, a corner bracket having three parts correspondingly related, one of said parts being arranged to engage the inner surface of one wall while the other two parts are arranged to overlie the adjacent surface of the other walls, and means connecting the first mentioned part to the wall whose inner surface it engages, the other two parts having portions interlocking with portions of the walls which said parts overlie.

2. In a construction of the character set forth, the combination of three walls disposed at a given angle one to the others, a corner bracket having three parts correspondingly related, one of said parts being arranged to engage the inner surface of one wall while the other two parts are arranged to overlie the adjacent outer surface of the other walls, and means connecting the first mentioned part to the wall whose inner surface it engages, the other two parts having tongues extending through slots in the walls which said parts overlie.

3. In a construction of the character set forth, the combination of three walls disposed at a given angle one to the others, the inner side of one of the walls engaging the ends of the others, a corner bracket having three parts that are disposed one to the others at the aforesaid given angle, one of said parts being arranged to engage said inner side of said first mentioned wall and

the other parts extending over the ends of the other walls and overlying their outer surfaces, the ends of said walls being cut away to accommodate said bracket, and 5 means securing the walls to the respective parts of the bracket.

4. In a construction of the character set forth, the combination of three walls, each of which is disposed at right angles to the 10 others, a corner bracket having three parts correspondingly related, one of said parts engaging the inner surface of one wall while the other two parts overlie the outer surfaces of the other walls, means securing the 15 walls to the respective parts of the bracket, the parts of the bracket overlying said other walls having tongues that are offset outwardly from their outer surfaces, and a leg of angle formation embracing the corner 20 formed by the meeting of said other walls and having its end engaged beneath the aforesaid tongues of the corner bracket, and means securing the leg to the structure so as to prevent the withdrawal of its end from 25 beneath said tongues.

5. In a construction of the character set forth, the combination of a top wall, two vertical walls disposed at right angles to each other, a corner bracket having three 30 parts each of which is disposed at right angles to the other parts, one of said parts being arranged for engagement with the under surface of the top wall while the other two parts overlie the outer surfaces 35 of the vertical walls adjacent their upper ends, means securing the walls to respective parts of the bracket, the parts of the bracket which overlie the vertical walls having outwardly and downwardly projecting tongues, 40 a leg of angle formation embracing the corner formed by the meeting of the vertical walls and having its upper end engaged beneath the tongues of the bracket, a base supported horizontally within the vertical 45 walls a suitable distance below the top, and means securing the base, the vertical walls, and the leg together.

6. In a construction of the character set forth, the combination of a top wall, an end 50 panel having its upper edge engaging the underneath surface of the top wall, the front edge of the end panel being flanged inwardly at right angles, a corner bracket comprising a horizontal part overlying the upper ends of the end panel and its right angle 55 flange and having depending parts at right angles to the former part and at right angles to each other and which overlie respectively the end panel and its flange, means securing the depending parts of the bracket to the end panel and flange, said depending parts having lugs extending through slots in the panel and its flange and being provided with outwardly and downwardly extending 60 tongues, a gusset having a vertical wall 65 engaged against the flange of the end panel and having a right angle flange engaging the outer surface of the end panel, the gusset being provided with a horizontal flange at its upper edge which is at right angles to the former flange and which is adapted to be supported in the plane of the upper edge of the end panel, a leg of angle formation embracing the corner formed by the meeting of the end panel and its flange, the gusset being confined between said parts and the leg, while the upper end of the leg is engaged beneath the tongues of the corner bracket, means securing the leg to the end panel at a point spaced a suitable distance below the top, and means for securing the top to the horizontal part of the corner bracket and to the horizontal flange of the gusset.

7. In a construction of the character set forth, the combination of a top wall, an end panel having its upper edge engaging the underneath surface of the top wall, the front edge of the end panel being flanged inwardly at right angles, a corner bracket 70 comprising a horizontal part overlying the upper ends of the end panel and its right angle flange, the panel and flange being cut away to a depth substantially equal to the thickness of the said horizontal part of the bracket, the bracket having depending parts 75 at right angles to the former part and at right angles to each other and which overlie respectively the end panel and its flange, means securing the depending parts of the bracket to the end panel and flange, said depending parts having lugs extending through slots in the panel and its flange and being provided with outwardly and downwardly extending tongues, a gusset having a vertical wall 80 engaged against the flange of the end panel and having a right angle flange engaging the outer surface of the end panel, the gusset being provided with a horizontal flange at its upper edge which is at right angles to the former flange and which is adapted to be supported in the plane of the upper edge of the end panel, a leg of angle formation embracing the corner formed by the meeting of the end panel and its flange, the gusset being confined between said parts and the leg, while the upper end of the leg is engaged beneath the tongues of the corner bracket, means securing the leg to the end panel at a point spaced a suitable distance below the top, and means for securing the top to the horizontal part of the corner bracket and to the horizontal flange of the gusset.

8. In a construction of the character set forth, the combination of an end panel having a right angle flange at its forward edge, a corner bracket having a horizontal part disposed above the corner formed by the end 85 panel and flange, the horizontal part of the bracket having a vertical wall engaged against the flange of the end panel and having a right angle flange engaging the outer surface of the end panel, the horizontal part of the bracket being provided with a horizontal flange at its upper edge which is at right angles to the former flange and which is adapted to be supported in the plane of the upper edge of the end panel, a leg of angle formation embracing the corner formed by the meeting of the end panel and its flange, the horizontal part of the bracket being confined between said parts and the leg, while the upper end of the leg is engaged beneath the tongues of the corner bracket, means securing the leg to the end panel at a point spaced a suitable distance below the top, and means for securing the top to the horizontal part of the corner bracket and to the horizontal flange of the gusset.

9. In a construction of the character set forth, the combination of an end panel having a right angle flange at its forward edge, a corner bracket having a horizontal part disposed above the corner formed by the end 90 panel and flange, the horizontal part of the bracket having a vertical wall engaged against the flange of the end panel and having a right angle flange engaging the outer surface of the end panel, the horizontal part of the bracket being provided with a horizontal flange at its upper edge which is at right angles to the former flange and which is adapted to be supported in the plane of the upper edge of the end panel, a leg of angle formation embracing the corner formed by the meeting of the end panel and its flange, the horizontal part of the bracket being confined between said parts and the leg, while the upper end of the leg is engaged beneath the tongues of the corner bracket, means securing the leg to the end panel at a point spaced a suitable distance below the top, and means for securing the top to the horizontal part of the corner bracket and to the horizontal flange of the gusset.

panel and its flange and having depending portions overlying the outer surfaces of said parts, means permanently securing the corner bracket to the end panel, a top adapted to rest upon the end panel and upon the horizontal part of the corner bracket, means for detachably connecting the top to said bracket, a gusset within the angle between the top and the end panel and adapted to interfit with parts of the corner bracket, means for detachably connecting the top to said gusset, and a leg adapted to embrace the corner formed by the end panel and its flange and to confine between said parts and itself the aforesaid gusset, the bracket having a leg receiving part into holding engagement with which the leg is adapted to be presented upwardly, and means for detachably connecting the leg to the end panel 20 to withhold it against downward movement.

9. In a construction of the character set forth, the combination of a horizontal top wall, vertical walls disposed at right angles to each other and whereon the top is supported, a corner bracket secured to the upper ends of the vertical walls, said bracket having a leg receiving portion into which a leg is adapted to be inserted upwardly, means detachably connecting the top to the corner bracket, and a leg of angle formation designed to embrace the corner formed by the meeting of the vertical walls and adapted to have its end engaged within the leg receiving part of the bracket, and means for detachably connecting the leg to the structure so as to prevent the withdrawal of its upper end from the leg receiving part of the bracket.

10. In a construction of the character set forth, the combination of vertical walls arranged at right angles to each other to form a corner, a corner bracket having a horizontal portion engaging the tops of the vertical walls and two depending parts overlying the outer surfaces of the vertical walls, means securing the bracket to the walls, the depending parts of the bracket having tongues which extend outwardly and downwardly therefrom, a leg of angle formation embracing the corner formed by the vertical walls and having its upper end engaged beneath the tongues of the bracket, means securing the leg against vertical movement with respect to the walls thereby to prevent the withdrawal of its upper end from beneath the aforesaid tongues, a top resting upon the vertical walls, and means connecting the top to the horizontal part of the bracket.

60 11. A stove structure comprising a rectangular top, end panels, and a member extending between and connecting the end

panels, four brackets situated at the respective corners of the structure, each having three parts disposed at right angles one to the others, one part being attached to the top and another part to an end panel, the brackets involving guide members, a leg slidable into the guide members of each bracket, and means for securing the legs to the structure to prevent their withdrawl from the guide members.

12. In a construction of the character set forth, the combination of a top wall, an end panel having its upper edge disposed beneath the underside of the top wall, the front edge of the end panel being flanged inwardly at right angles, a bracket comprising a horizontal part overlying the upper ends of the end panel and its right angle flange and having depending parts at right angles to the former part and at right angles to each other and which overlie respectively the end panel and its flange, means securing the bracket to the end panel, a leg of angle formation embracing the corner formed by the meeting of the end panel and its flange, the upper end of said leg interengaging with parts of the bracket thereby to be held against lateral displacement, and means securing the leg to the end panel at a point spaced a suitable distance below the top.

13. In a construction of the character set forth, the combination of a horizontal top wall, vertical walls whereon the top wall is supported, brackets secured to the upper ends of the vertical walls, said brackets having leg-receiving portions into which legs are adapted to be inserted upwardly, legs of angle formation designed to embrace the edges of the vertical walls and adapted to have their upper ends interengaged with parts of the bracket, and means for detachably connecting the legs to the structure so as to prevent disengagement of their upper ends from the brackets.

14. In a stove structure, the combination of a top, brackets whereon the top is supported, said brackets having leg receiving sockets, legs having their upper ends engaged in said sockets, and means securing the legs to the structure at points below said sockets.

15. In a stove of the character set forth, the combination of a top, a sub-structure whereon the top is supported, said sub-structure incorporating brackets having leg receiving sockets, legs having their upper ends engaged in said sockets, and means securing the legs to the substructure below the brackets.

In testimony whereof, I hereunto affix my signature.

LEE S. CHADWICK.
